TRANSLATING DEVICE.

Application filed June 6, 1925. Serial No. 35,425.

This invention relates to electrical movements for translating varying electrical impulses into mechanical motion, and aims particularly to provide an electrical movement 5 suitable for use with radio loud-speakers, line-wire receivers and the like. This electrical movement has special advantages when associated with diaphragms of the large conical type. However, as hereinafter 10 explained in detail it is suited to various other uses, as will be understood by those skilled in the art.

For a better understanding of the electrical movement of the present invention, 15 and of its capacity for advantageous cooperation with a loud-speaker diaphragm of the conical type, I have hereinafter described it in conjunction with a diaphragm of that type and particularly one so mounted 20 as to permit that free bodily movement of the cone which I have found best suited to give accurate tone production or reproduction.

Claims on the novel cone and its mounting, as disclosed in the present application, 25 are made in my co-pending application, Serial No. 34,255, filed June 1st, 1925. Other cones and other mountings can be used in conjunction with the electrical movement claimed herein, but for best results there 30 must be correct coordination between the electrical movement and the vibratory diaphragm. Due regard must be had to the weights of the several moving elements and to the magnitudes of their movements.

In the preferred embodiment of my present invention the electrical arrangement is such that the vibration of the armature is 35 of small amplitude.

The electrical movement of the present 40 invention includes a very rigid vibratory armature or reed, one end of which is securely anchored, and the other end of which is free to vibrate. The free-end portion is normally disposed midway between two 45 electro-magnet poles which are in turn secured to one pole of a strong permanent magnet, so that both electro-magnet poles have the same normal polarity and normally exert equal and opposing forces on the free 50 end of the armature. The two electro-magnet poles are those of a single soft iron pole piece and on each of them there is

mounted a coil through which the actuating or speech current circulates, thereby causing fluctuating differences of magnetic attraction between the armature or reed and the electro-magnet poles. The structure may be regarded as including a polarized reed with its free end positioned between opposing speech coils through either or both of which the magnetic flux of said reed may pass. Current fluctuations in the speech coils cause the armature or reed to vibrate correspondingly and the vibrations thus set up in the reed may be representative of 60 and capable of being translated into sound waves.

I have discovered that distinctly improved results in electrical movements of the type now being discussed are obtainable with a 70 very rigid armature, the natural frequency of which is above good audibility, or at least higher than the ordinary musical scale, and with the connecting link between armature and diaphragm attached to the armature at 75 a point between the fixed end thereof and the portion thereof adjacent the electromagnet poles. The exact point for best attachment to the armature can be found by trial. Under these conditions the amplitude of vibration of the diaphragm is less than the amplitude of vibration of that portion of the armature which is directly acted upon by the electromagnet. This is contrary to the usual loud speaker arrangement, wherein 80 a step up actuation of the diaphragm is provided for. My present arrangement is particularly suited for use with a conical diaphragm which is very rigid and light in weight and restrained at the periphery as 85 little as possible, so that the diaphragm may vibrate substantially as a whole instead of bending in the manner of an ordinary diaphragm. Although the best results in 90 radio and line wire receivers are realized only with a very rigid, light and freely moving diaphragm, still, fair results may be had with a diaphragm which could not be regarded as meeting those qualifications, and the invention should, therefore, not be 95 construed as limited in those respects except in so far as such limits are included in the appended claims.

Other features, characteristics and ad-

vantages of the present invention are pointed out hereinafter.

Fig. 1 is a sectional elevation of a loud-speaker constructed in accordance with this 5 invention;

Fig. 2 is a fragmentary sectional view of a modified form of conical diaphragm;

Figs. 3, 4 and 5 are side, top and rear 10 views, respectively, of the electrical movement used for actuating the diaphragm;

Fig. 6 is a view partly in cross section of the electrical movement and on a larger scale than Figs. 3, 4 and 5;

Fig. 7 is a view partly in cross section 15 taken along the lines 7-7 of Fig. 6, and

Fig. 8 is a rear elevation of the receiver with the electrical movement removed.

The conical diaphragm 1 is preferably of 20 large diameter, usually more than nine inches, and generally is made wholly or in part of paper in order that it may be of light weight. The paper should be stiff.

A long fibered paper of porous structure 25 and free from "loading" will serve well, and any sizing should be of the fibers before felting and not of the sheet after it has been formed up. A layer of varnish or other like material applied to a finished cone is likely to impair greatly its sound 30 producing qualities. Brittleness in the cone is a desirable characteristic, provided the paper has at the same time sufficient toughness to withstand commercial transportation and ordinary handling during use.

35 It has been my experience that paper several years old is better than new stock, presumably because of an increased stiffening of the fibers due to ageing. In any event, the paper used for the cone must be capable 40 of being bent without breaking, in order that there may be formed in it the one or more peripheral creases or bends on which I rely for free bodily movement of the diaphragm when in use.

45 In making the diaphragm illustrated a flat sheet of paper is first cut to form a sector of the required radius and angle. This sector of paper is then creased circumferentially at a lesser radius or radii to mark 50 out the line or lines on which the paper may be sharply bent to bring about the results desired by me.

55 During the process of forming the flat sector into a cone those portions of the paper sheet which are to form the supporting brim are pressed one way or the other as the case may be so that they will assume their proper plane. The cone is then glued along 60 its radial joint. By forming the complete cone this way the brim or circumferential corrugation is formed without any substantial distortion of the paper such as might cause the main portion of the diaphragm to

buckle in spots or become unequally stretched 65 or tensioned.

As an alternative procedure I may cut the sector from the flat sheet of paper and glue it to form a cone, and then by means of a suitable tool crease the cone near its 70 edge and crowd the periphery forward until by bending sharply at crease 2 it snaps into the position shown in Fig. 2. Similar circumferential creasing on the lines 2' and 2'' will produce the triple bend or corrugation of Fig. 1. From experience I have found that with a single bend as shown in Fig. 2 the forwardly flaring brim of the cone naturally takes up a position making the same angle to the vertical as does the main 80 body of the cone. I consider this feature of importance because of the freedom from irregular strains in the cone, and because it contributes to that freedom of bodily movement for the cone which I have found to 85 be so vital to the most satisfactory sound production or reproduction.

By virtue of a circumferential bend or plurality of bends and the rigidity of the paper of which the diaphragm is made, the 90 main portion of the diaphragm is enabled to vibrate substantially as a whole, that is to say, with little or no bending of the cone. This results in much more accurate reproduction than is possible with a diaphragm 95 subjected to bending action. Best results are had by having a part, but not all, of the brim of the cone secured to a supporting structure, the remaining or inner portion of the brim being relied on for flexibility in giving to the cone proper the needed support and restraint, but at the same time allowing it to move axially much as if it were without support. Any arrangement 100 for supporting the diaphragm so that it is capable of moving bodily with but little restraint may be employed instead of bending or corrugating the peripheral portion 105 of the diaphragm as above described, but the arrangement shown is inexpensive, is 110 attractive in appearance, and serves its purpose well.

The supporting structure for the diaphragm and for the electrical movement or electromagnetic actuating mechanism comprises a spun or pressed sheet metal member 3 of frusto conical shape having an offset rim with a beaded edge 4 formed as shown to receive the diaphragm. The metal bead 4 protects the edge of the cone from 115 mechanical injury. The brim of the diaphragm lies flat against the metal rim and is preferably cemented thereto but is enough wider than the rim to provide the desired elastic support for the cone. The sheet metal 120 member 3 is provided with a large central opening 5 into which the electrical movement 125 is removably inserted. A post 6, which may

be of cast iron or brass, is riveted or otherwise secured to the sheet metal member 3 and in turn is secured to the cast metal base 7 by means of a stud 8 and nut 9. The sheet metal member 3 is preferably provided with openings as shown at 10, 11 and 12 for the purpose of facilitating the passage of sound waves from the inside of the instrument to the unconfined air. The openings 10, 11 and 12 may be of ornamental outline. The electrical movement comprises a U-shaped permanent magnet 13, the two ends of which are slotted as indicated at 14 and 15. To one pole of the permanent magnet there is secured a soft iron pole piece 16. The pole piece 16 is secured to the permanent magnet by means of a screw 17. Threaded studs 18 and 19 constitute poles for the pole piece 16 and are adjustable therein, toward and away from each other. Between the arms of the pole piece 16 there is inserted a specially formed block 20 of insulating material, such as bakelite, having recesses of proper size to receive the electromagnet coils 21 and 22, each of which surrounds one of the studs 18 and 19. The central openings through the coils 21 and 22 are of the proper size to fit the unthreaded portions of studs 18 and 19. The coils 21 and 22 should be securely gripped within the block 20 and if necessary they may be cemented in place. The block 20 should make a snug fit between the arms of the pole piece 16, and the unthreaded portions of the studs 18 and 19 should fit snugly within the openings through the coils 21 and 22. A very rigid soft iron armature or reed 23 is firmly bolted at one end to one pole of the permanent magnet and its free end is normally situated midway between the ends of the poles formed by studs 18 and 19. Normally the polarity of these poles is the same and they are so adjusted that their magnetic attractions on the armature 23 are equal and opposing.

A rod 24 is rigidly attached at one end to the armature 23 at a point between its secured end and that part which is disposed between the electromagnet poles. The other end of rod 24 is attached to the center of the diaphragm by means of set screws 25. Rod 24 forms a connecting link between and functions to transmit the vibrations of the armature 23 to the diaphragm 1. In order to provide a secure attachment to the center of the diaphragm, it is reinforced by means of a pair of conical washers 26 secured together, with the diaphragm between, by means of a hollow rivet 27 through which the rod 24 extends.

Coils 21 and 22 are so wound that current passing one way will cause an attraction of armature 23 toward one of the electromagnet poles and vice versa.

The diaphragm actuating mechanism, in-

cluding permanent magnet, armature, connecting link and coils forms a self contained unit which is mounted on a metal plate 28 through the medium of a wooden block 29 to which the permanent magnet is secured by means of a three-armed clamping plate 30, which embraces the permanent magnet, and a pair of wood screws 31. Plate 28 is secured to the sheet metal supporting member 3 by means of four machine screws 32. A lifting handle 33 is attached to plate 28 and affords a convenient means for carrying the instrument about.

Although I do not wish to be limited by any theory for the highly satisfactory results obtained by me in sound reproduction through use of the apparatus above described as a loud speaker on radio and line wire circuits, nevertheless, I record my present ideas on the subject. The armature 23 being of metal and relatively thick and stiff has a natural vibratory period above audibility. The magnetic flux from that pole of the permanent magnet to which the armature is rigidly attached streams across the armature toward the other pole of the permanent magnet, and at or near the free or vibratory end of this armature that flux is split into two parts, one part going through soft pole 18 to the soft iron pole shoe 16, and thence to the permanent magnet, and the other part going through the pole 19. Poles 18 and 19 are adjustable, and by longitudinal movement can be so positioned that the magnetic flux is normally split into two equal portions. This adjustment can be made at the factory and the poles can be permanently clamped in their adjusted position by suitable transverse bolts passing through the slotted pole shoe.

A current impulse through the speech coils 21 and 22 redistributes the magnetic flux which streams out of armature 23 into the adjustable poles 18 and 19 so that more than half of it goes to one pole, say pole 18. The armature 23 then moves toward pole 18 and by its movement decreases the air gap thereby increasing the flux to that pole and increasing the magnetic pull of that pole on the armature. The results are therefore cumulative and the attracting pole pulls magnetically with more and more force while the opposing pole pulls with a progressively decreasing force. The natural elasticity of armature 23 is sufficient to permit flexing of it, but the armature is so stiff and is so supported at one end that it cannot strike the adjustable pole toward which it moves. A current impulse through the speech coils in the opposite direction will produce a flexing of the armature toward pole 19, and the swinging armature is thus made to take up movements which in frequency and in magnitude represent the current variations

in the speech coils. Bar 24 is rigidly attached to armature 23 between the vibratory end and the supported end of that armature. This I regard as an important innovation. There is a gain in power but a loss in the magnitude of movement.

The exact point at which bar 24 can best be attached to armature 23 lies about midway of the length of the armature, and depends somewhat on the thickness and stiffness of the armature, and on the weight and other characteristics of the diaphragm to which bar 24 is rigidly attached. The point can best be found by trial.

The diaphragm which can best be used with this electrical movement is of the conical type, and preferably not less than 9" in diameter. The fibrous material of which the cone is made should be light in weight and relatively stiff. A porous paper, the individual fibers of which are tightly interlocked with one another and have been rendered stiff by sizing or ageing, will serve well. Stiffness or brittleness acquired by filling the interstices between the fibers of the paper, as with varnish, does not help. Free suspension of the cone so that it may move as a whole without local warping or bending is helpful and important. Bending up a circumferential brim at a relatively sharp angle and allowing the brim to assume its own natural angle with respect to the vertical (which as it happens is substantially that subtended by the cone itself) and then furnishing mechanical support to the brim through a part only of its width gives to the cone as a whole that freedom of bodily movement that I have found so highly desirable, while at the same time making the structure rugged enough for merchantability.

By thus coordinating the diaphragm to the electrical movement a highly satisfactory loud speaker can be obtained. Its tonal characteristics can be varied somewhat by changing the weight or stiffness of the vibratory armature or reed, or by changing the weight, size or thickness of the fibrous cone. For best speech reproduction the treble should be emphasized, and for best reproduction of music the base tones should be emphasized. As to the lower tones of the musical scale, my loud speaker presents great advantage over any structure within my observation where movement of a small flat diaphragm of the telephone type is amplified through a horn. My loud speaker is entirely free from the unpleasant or "horny" timbre of loud speakers of the horn type.

This invention is capable of considerable variation and modification and should not be construed as limited to the particular

structure described and illustrated, except as required by the appended claims.

I claim:

1. In a translating device, the combination of a permanent magnet, a resilient reed supported at one end by a pole of said magnet and polarized thereby, two poles of a speech magnet on opposite sides of the free end of said resilient reed and between which the end of said reed projects, and means for translating into sound the vibratory movements of said reed. 70 75

2. In a translating device, the combination of a permanent magnet, a resilient reed rigidly attached at one end to a pole of said magnet and polarized thereby, two poles of a speech magnet on opposite sides of the central plane of said permanent magnet and between which the free end of said resilient reed projects, and means for translating into sound the vibratory movements of said reed. 80 85

3. In a translating device, the combination of a U-shaped permanent magnet, a resilient polarized vibratory armature supported at one end on a pole of said magnet and polarized thereby, a bifurcated pole shoe embracing the other end of said armature and between the two poles of which the end of said armature projects, a speech winding in magnetizing relation to said pole shoe and with its axis perpendicular to the plane of said magnet, and means for translating into sound the vibratory movements of said armature. 90 95

4. In a translating device, the combination of a permanent magnet, a polarized vibratory reed supported thereon at one end and through which the magnetic flux of said magnet passes longitudinally, a bifurcated pole shoe embracing the other end of said armature and between the two poles of which the end of said armature projects, a speech winding on each side of the free end of said reed and in magnetizing relation to said pole shoe, and a conical diaphragm operatively connected to said armature to translate into sound the vibratory movements of said armature. 100 105 110

5. In a translating device the combination of a magnet, a vibratory armature supported at one end by a pole of said magnet and polarized thereby, a bifurcated pole shoe embracing the other end of said armature and between the two poles of which the end of said armature projects, a speech winding in magnetizing relation to said pole shoe, and a transmission rod extending at right angles to the plane of said magnet and connected to said armature intermediate its ends and substantially perpendicular thereto. 115 120 125

6. In a translating device the combination of a permanent magnet, a polarized vibra-

5. A vibratory reed rigidly supported at one end by a pole of said magnet, a bifurcated pole shoe embracing the other end of said reed and between the two poles of which the end of said reed projects, a speech winding in magnetizing relation to each bifurcation of each pole shoe, and means for translating into sound the vibratory movements of said reed. 65
6. In a translating device the combination of a permanent magnet, a polarized vibratory reed rigidly supported at one end by a pole of said magnet and polarized thereby, a bifurcated pole shoe embracing the other end of said reed and between the two poles of which the end of said reed projects, a speech winding in magnetizing relation to each bifurcation of said pole shoe, a transmission rod extending at right angles to the plane of said magnet, and a diaphragm connected to said rod and having its periphery positioned in a plane parallel to that of said permanent magnet. 70
7. In a translating device the combination of a magnet, a vibratory reed supported at one end by one pole of said magnet and through which the magnetic flux of said magnet passes longitudinally, a pole shoe for the other pole of said magnet, said shoe having two poles on opposite sides of the free end of said reed and between which said free end projects, a speech coil for each shoe pole, and means for translating into sound the movements of said armature produced by said speech coils. 75
8. In a translating device the combination of a magnet, a vibratory reed supported at one end by one pole of said magnet and through which the magnetic flux of said magnet passes longitudinally, a pole shoe for the other pole of said magnet, said shoe having two poles on opposite sides of the free end of said reed and between which said free end projects, a speech coil for each shoe pole, and means for translating into sound the movements of said armature produced by said speech coils. 80
9. In a translating device, the combination of a magnet, a vibratory reed rigidly supported at one end by one pole of said magnet, a pole shoe for the other pole of said magnet, said shoe having two poles on opposite sides of the central plane of said magnet and between which the free end of said armature projects, a speech coil for each pole shoe, and means for translating into sound the movements of said armature produced by said speech coils. 85
10. In a translating device the combination of a permanent magnet, a vibratory reed rigidly supported at one end by one pole of said magnet and polarized thereby, a soft iron pole shoe for the other pole of said magnet, said shoe having two opposed soft iron poles on opposite sides of the free end of said armature and between which said end projects, a speech coil for each shoe, and means for translating into sound the movements of said armature produced by said speech coils. 90
11. In a translating device the combination of a permanent magnet, a flexible armature rigidly attached at one end to one pole of said magnet, said armature being polarized thereby, a soft iron pole shoe for the other pole of said magnet, said shoe having two opposed soft iron poles on opposite sides of the free end of said armature and between which said end projects, a speech coil for each pole shoe and means for translating into sound the movements of said armature produced by said speech coils. 95
12. In a translating device the combination of a permanent magnet, a flexible armature rigidly attached at one end to one pole of said magnet, a soft iron pole shoe for the other pole of said magnet, said shoe having two opposed adjustable poles on opposite sides of the free end of said armature and between which that free end projects, a speech coil encircling each shoe pole, and means, including a diaphragm, for translating into sound the movements of said armature produced by said speech coils. 100
13. In a translating device, the combination of a permanent magnet, a flexible armature rigidly attached at one end to one pole of said magnet and polarized thereby, a soft iron pole shoe for the other pole of said magnet, said shoe having two opposed adjustable poles on opposite sides of the free end of said armature and between which said free end projects, a speech coil encircling each shoe pole, and means, including a diaphragm, for translating into sound the movements of said armature produced by said speech coils. 105
14. In a translating device the combination of a permanent magnet, a polarized reed rigidly supported at one end, a pole shoe adjacent the other end of said reed, said shoe having two poles on opposite sides of the free end of said reed and between which that free end projects, and a speech coil for each pole shoe, each of said coils being held in stationary position with respect to the pole shoe and each pole being axially rotatable in the pole shoe and longitudinally adjustable through its speech coil. 110
15. In a translating device, the combination of a U-shaped permanent magnet, a polarized reed rigidly secured at one end to a pole of said magnet and polarized thereby, a soft iron pole shoe adjacent the other end of said reed, said shoe having two poles on opposite sides of the free end of said reed and between which that free end projects, and a speech coil for each pole shoe, each of said coils being held in stationary position with respect to the pole shoe, and each pole being axially rotatable in the pole shoe and longitudinally adjustable through its speech coil. 115
- In testimony whereof I affix my signature.
- MARCUS C. HOPKINS.
